UNITED STATES PATENT OFFICE

155,585

DESIGN FOR A BOX

Benjamin F. Conner, West Hartford, Conn., assignor to Colt's Manufacturing Company, a corporation of Connecticut

Application January 10, 1947, Serial No. 136,045

Term of patent 7 years

(Cl. D58—13)

To all whom it may concern:

Be it known that I, Benjamin F. Conner, a citizen of the United States, residing at West Hartford, in the county of Hartford and State of Connecticut, have invented, a new, original, and ornamental Design for a Box, of which the following is a specification, reference being had to the accompanying drawing, forming part thereof.

In the drawing:

Fig. 1 is a top plan view of a box, embodying my new design.

Fig. 2 is a front elevational view thereof.

Fig. 3 is an end elevational view thereof.

Fig. 4 is another end elevational view with the cover partially raised.

I claim:

The ornamental design for a box, as shown and described.

BENJAMIN F. CONNER.
